(57) **CLAIM**

The ornamental design for an applicator as shown and described.

DESCRIPTION

FIG. 1 is a perspective view of an applicator showing the new design;

FIG. 2 is a front view of the applicator of FIG. 1 showing the new design;

FIG. 3 is a rear end view of the applicator of FIG. 1 showing the new design;

FIG. 4 is a left side view of the applicator of FIG. 1 showing the new design;

FIG. 5 is a right side view of the applicator of FIG. 1 showing the new design;

FIG. 6 is a top view of the applicator of FIG. 1 showing the new design;

FIG. 7 is a bottom view of the applicator of FIG. 1 showing the new design;

FIG. 8 shows a front perspective view of the cap of the applicator of FIG. 1 shown separately to show aspects of the design that are not visible when combined;

FIG. 9 shows a rear perspective view thereof; and,

FIG. 10 shows an exploded view of the applicator of FIG. 1.

1 Claim, 6 Drawing Sheets
